UNITED STATES PATENT OFFICE.

JOHN A. WIGAL, OF TYNER, WEST VIRGINIA, ASSIGNOR OF ONE-HALF TO
THOMAS M. WIGAL, OF SAME PLACE.

BELT-TIGHTENER.

SPECIFICATION forming part of Letters Patent No. 398,361, dated February 19, 1889.

Application filed October 25, 1888. Serial No. 289,131. (No model.)

To all whom it may concern:

Be it known that I, JOHN A. WIGAL, a citizen of the United States of America, residing at Tyner, in the county of Wood and State of West Virginia, have invented certain new and useful Improvements in Belt-Tighteners; and I do hereby declare the following to be a full, clear, and exact description of the invention, such as will enable others skilled in the art 5 to which it appertains to make and use the same, reference being had to the accompanying drawings, and to letters or figures of reference marked thereon, which form a part of this specification.

15 My invention relates to an automatically-operating expansible pulley or belt tightener; and it consists in the novel construction and combination of parts, as will be more fully hereinafter described and claimed.

20 The object of my invention is to provide a pulley of the character set forth for the purpose of taking up slack in the belt without adjustment by hand, the parts thereof being simple and effective in their construction and 25 operation, and strong and durable. I attain this object by the construction illustrated in the accompanying drawings, wherein like letters of reference indicate similar parts in the several views, and in which—

30 Figure 1 is a side elevation of my improved pulley shown as applied. Fig. 2 is a similar view of the pulley detached, showing one of the connections removed. Fig. 3 is a detail perspective view of one of the sections of the 35 pulley.

A and A' indicate the two sections of the pulley, each of which in dimension is less than half of a true circle. On each side of the center of each of said sections parallel 40 ribs a are formed, and in the web between said ribs, near the curved side of each section, elongated slots a' are formed. The central part of each section between the ribs a is also formed with an inclined semi-elliptical slot, 45 a², adapted to be engaged by an elliptical cam, B, on the driving-shaft B', driven by said pulley. The slots a², when united, form a recess sufficiently large to close in the said cam B when the sections A and A' bear against

each other, as will be more fully hereinafter 50 set forth.

In the spaces inclosed by the ribs a in the sections connecting-strips C are mounted on each side of said sections, and are secured to each other by rivets or pins c, passing through 55 apertures at their outer ends and through the elongated slots a' in the sections. By said connecting-strips C the sections A and A' of the pulley are held united.

The belt D is readily placed over the pulley by the contracting construction thereof. When the drive-shaft B' revolves, the cam B thereon bears against the walls of the two oppositely-situated cam slots or recesses a², respectively, at the upper part of one and the 65 lower part of the other, thus forcing the two sections A and A' apart, and taking up the slack of the belt the said pulley is revolved and transmission of power effected. So long as the belt D is of the desired tension the 70 cam B holds to the position just described. As soon, however, as the tension of the belt is slackened or relaxed through stretching thereof or from other causes, the cam will force the sections A and A' still farther apart 75 and compensate for or take up said slack. In the movement of the sections A and A' they are guided and held true by the connecting-strips C, upon which they slide, as hereinbefore referred to.

Having thus described my invention, I claim—

1. The combination, substantially as described, of an automatically-expansible pulley, consisting of two semicircular sections 85 having cam-slots centrally arranged in their meeting edges and united by sliding connecting-strips, and a shaft provided with a cam constructed to fit said cam-slots.

2. A pulley constructed in two sections having central ribs and cam recesses or slots, in combination with the connection-strips, the drive-shaft, and the cam engaging the cam recesses or slots for expanding said sections, substantially as described.

3. The combination, substantially as described, of a pulley composed of two equal independent sections having centrally-arranged

80

95

cam-slots in their meeting edges, and on each side of said cam-slots ribs formed at right angles to said meeting edges, elongated slots arranged parallel with the ribs, connecting 5 strips seated between said ribs and united at their outer ends by pins passing through the elongated slots, a shaft, and a cam fixed on the shaft and shaped to fit the cam-slots in the meeting edges of the sections.

In testimony whereof I affix my signature in presence of two witnesses.

JOHN A. WIGAL.
